Primary Examiner — Sandra S Snapp*Assistant Examiner* — Katherine Glennon(74) *Attorney, Agent, or Firm* — Leason Ellis LLP(57) **CLAIM**

The ornamental design for a clock radio, as shown and described.

DESCRIPTION

FIG. 1 is a front perspective view of a clock radio according to my new design, illustrating a cloth grill in the rear top and side portions of the design;

FIG. 2 is a front view of the design of FIG. 1;

FIG. 3 is a rear view of the design of FIG. 1;

FIG. 4 is a left side view of the design of FIG. 1;

FIG. 5 is a right side view of the design of FIG. 1;

FIG. 6 is a top view of the design of FIG. 1; and,

FIG. 7 is a bottom view of the design of FIG. 1.

The dash-dash broken lines, including USB ports, plugs, charging surfaces, and feet, illustrate environmental structure and form no part of the claimed design.

Conventional reflection lines, contour lines and shading are illustrated for purposes of highlighting the solid-rendering, but form no part of the claimed design.
